(57) CLAIM

The ornamental design for a shoe sole, as shown and described.

DESCRIPTION

FIG. 1 is a bottom perspective view showing my new design for a shoe sole,

FIG. 2 is a bottom plan view thereof,

FIG. 3 is a left side view thereof,

FIG. 4 is a right side view thereof,

FIG. 5 is a front view thereof; and,

FIG. 6 is a back view thereof.

The surfaces which are not shown, form no part of the claimed design.
